UNITED STATES PATENT OFFICE.

EUGENE ROBERTS, OF SALT LAKE CITY, UTAH, ASSIGNOR TO THE WESTERN STATES MACHINE COMPANY.

MEANS FOR MOUNTING AND DRIVING CENTRIFUGAL MACHINES.

1,383,568.

Specification of Letters Patent.

Patented July 5, 1921.

Application filed February 14, 1918. Serial No. 217,156.

To all whom it may concern:

Be it known that I, EUGENE ROBERTS, citizen of the United States, and resident of Salt Lake City, county of Salt Lake, State 5 of Utah, have invented certain new and useful Improvements in Means for Mounting and Driving Centrifugal Machines, of which the following is a specification.

This invention relates to the centrifugal 10 machine art and has for its object the provision of an efficient, durable and reliable suspension and drive for centrifugal baskets of the type commonly used in sugar factories and for other purposes.

15 As is known to those skilled in the art, the peculiar conditions attending the use of this class of heavy centrifugal machines involving the suspension and rotation of a heavy unbalanced mass of sugar which together with the weight of the basket may 20 weight 1200 or 1500 lbs., make peculiarly difficult the provision of a fully efficient, satisfactory and durable suspension and driving means adequate to meet such conditions.

25 One of the serious difficulties lies in the tendency to a chattering or vibration of the bearings employed for giving a rotary and gyratory suspension to the basket shaft due 30 to the powerful lateral shocks to which these bearings are subjected by the violent swaying of the centrifugal machine when coming up to speed with an unbalanced load. Another problem peculiar to this art that has 35 afforded difficulty is the necessity for using motors of much larger size and cost than are required to keep the machines in normal operation owing to the necessity of frequently stopping and starting the machines 40 within a minimum period of time. It is the object of the present invention to afford improvements tending to minimize or overcome the difficulties above mentioned and others as well that are incident to the operation 45 of centrifugal machines of the suspended type for heavy work.

To this end the invention comprises a principle of construction and arrangement designed to overcome or minimize the tendency 50 of the suspended shaft and of its oscillatory head to raise from the supporting seat under the impact of sidewise shock, and the invention further consists in a principle of construction and arrangement by 55 which a large loss of power is avoided

through maintaining the driving shaft and its motor in continuous operation without intermittent stopping and braking by affording an intermittent connection between an overhead fixed drive shaft, and the underneath suspended basket shaft through the agency of an intermediate connecting shaft supported in fixed bearings and having permanent but flexible coupling connection with the basket shaft, and having also 60 intermittent clutch connection with the overhead driving shaft.

These and other features of the invention will be explained in detail in this specification and will be defined in the claims annexed hereto.

In the accompanying drawings I have illustrated one of the forms embodying the principles of the present invention in which—

Figure 1 is a vertical elevation partly in section showing the arrangement for mounting and driving the centrifugal basket by means of an overhead shaft.

Fig. 2 is a cross section on the plane indicated by section line 2—2 of Fig. 3.

Fig. 3 is an enlarged detail vertical sectional view showing more completely the details of the bearing head construction in connection with the supporting hanger.

In the practice of my invention according to the form illustrated in the drawings, I provide a fixed hanger preferably made in two separable sections a, a' fitting one inside of the other connected together detachably by suspension bolts. In the upper part of said hanger is mounted a bearing or centralizing plate a^2 having anti-friction bearing sleeve a^3 affording lateral bearing support for the transmission shaft e . This bearing plate a^2 is provided with a duct or passage a^4 for the admission of oil or grease to the bearing directly supporting the basket shaft, and also has a depending annular flange a^5 adapted to firmly engage a yielding annular buffer c , carried inside an upwardly extending annular flange b' of an oscillatory bearing head b .

The bearing head b is substantially in the form of a hollow cylinder having near its upper end a downwardly projecting bearing ring b^2 which on its inner surface is concavely and spherically curved on a center coinciding with the center of oscillation of the basket shaft. This concave bearing

ring rests upon a convex supporting spherical bearing ring or flange a^6 rigidly carried in the fixed hanger section a' .

To protect the elastic buffer c which is commonly made of vulcanized rubber from the action of oil in the bearing head, I provide a protecting ring a^9 slipped over the outside of the annular flange a^5 and overlapping the inside upper end of the bearing head b with which it has spherical contact so that the bearing head may oscillate while retaining close contact with said protective member a^9 .

In this class of centrifugal machines a large mass of raw sugar is dumped into the basket after which the basket is brought up to a speed of about 1100 R. P. M. The sugar thus dumped into the basket is very unevenly distributed and the result is the violent side sway of the basket until the load has become evenly distributed which involves a severe shock laterally which it is the object of the elastic buffer c to yieldingly oppose. With the arrangements herebefore in use, this violent side thrust or shock had a tendency to lift the oscillatory head from its bearing seat, and to at the same time, slightly de-centralize the bearing head, so that upon the return of the bearing head to its proper position on its bearing seat, there resulted a violent chattering or vibration of bearings which is not only detrimental to the operation of the machine, but which imposes a very severe wear on the bearings.

In my present construction and arrangement there are three features all of which contribute to minimizing or overcoming this objectional chattering or vibration of the bearings. First, the oscillatory bearing for supporting the bearing head from which the gyratory basket shaft is suspended, is located above the center of oscillation, that is, on the opposite side of the center of oscillation from the basket load. Second, the centralizing elastic buffer is located on the inside of the bearing head so that, that portion of the buffer that is compressed by the side-wise sway of the basket, is arranged to also resist the lifting of the bearing head from its bearing seat instead of acting as a fulcrum to permit such lifting as in the case where an external buffer is used. A third feature contributing to overcome this difficulty by making impossible any de-centralization of the bearing head even should it lift ever so little from its seat, resides in the use of a supplemental bearing located around the center of oscillation of the bearing head, and having spherical engagement with a centralizing member or portion of the stationary or fixed hanger.

More particularly the supplemental bearing as shown in the drawings comprises a convex spherically curved annular member

b^8 secured around the bearing head and concentric with the center of oscillation and having engagement with a concave co-operating surrounding bearing surface on the inside of the adjacent portion of the hanger. 70 As shown in the drawings, I prefer to make this concave bearing part a separate member b^4 which has a close piston fit with the cylindrical inside face of fixed portion a^6 of the hanger. The making of this bearing member b^4 as a separate piece, allows provision for wear, beside making the joint less rigid than if it were made integral with the hanger itself. Making the spherically curved convex bearing ring a^6 in a separate piece, 80 also tends to simplify the problem of manufacture and make easy the renewal of this part when worn. It should be understood that the curvature of the supplemental bearing and the main supporting bearing for the oscillatory head is concentric. Should any side-wise shock be powerful enough to raise the bearing head from its supporting seat, the supplemental bearing surface would keep the bearing head absolutely central 90 within the hanger, and thus obviates chattering or pounding which is seriously detrimental to the bearings.

The basket shaft is suspended in the oscillatory head in the following manner. A short shaft section d with its lower end tapered and having an enlarged head or ball d^{20} at its upper end, is provided with an encircling sectional sleeve comprising the upper member d' and the lower member d^2 100 formed with suitable shoulders to receive the ball bearing races d^6 and d^5 for supporting the shaft laterally inside the bearing head and adapted to receive the upper and lower ball bearing races d^3 d^4 which are arranged on opposite sides of the inwardly projecting ledge d^6 formed intermediate of the ends of the oscillatory head and arranged to receive the endwise thrust of the shaft in either direction through the medium of the upper and lower thrust bearings d^3 d^4 . This bearing ledge is provided with vertical passages b^6 which allow the oil or grease to pass from the upper into the lower portion of the bearing head for 110 maintaining lubrication of the bearings. The lower section d^2 of the shaft-encircling sleeve is supported in its position by means of the basket supporting head f fitted over the lower tapered end of the shaft d on 120 which it is firmly secured by means of the central nut f' on said shaft. The lower or basket end of the shaft f^2 is rigidly coupled to the suspension head f by means of suitable bolts. The head f is provided with an annular groove as shown at f^8 to receive the oil or grease sediment which may be drawn off through the opening f^9 normally closed by a screw plug or stopper. 125

From the upper end of the suspension 130

head f , extends an annular flange f^3 terminating in a cylindrical brake pulley member f^4 , around which is located the brake band f^5 by whose braking action the basket shaft 5 is stopped to permit discharge of the clarified sugar or other solid material.

The shaft bearing sleeve d' , d^2 is made in two sections to facilitate the assembling and taking down of the machine. The upper 10 sleeve section is inserted from the top of the shaft while the lower sleeve section is inserted from the bottom after the shaft has been placed in position, and when inserted carries the bearing race d^4 with it.

15 In the upper end of the shaft d quite close to the center of oscillation are inserted coupling pins d^{11} of preferably cylindrical form arranged to project upwardly and outwardly into interlocking engagement with 20 the notched or forked coupling member e' provided at the lower end of the transmission shaft e . The latter shaft is preferably concave to fit the convex spherical head d^{20} by which its weight is supported and with 25 which it remains in permanent contact during the operation of the machine. It is the object of this coupling to afford an efficient driving connection between the fixed or non-oscillatory shaft e and the gyratory rotary 30 basket shaft d , without subjecting the fixed bearings of the shaft e to side-wise stress or strain when the basket shaft oscillates.

Lubrication is afforded to the interior of 35 the bearing head for the flexible shaft couplings and the antifriction bearings, through the oil or grease duct a^4 . Lubrication is also afforded to the external spherical bearing b^3 by means of an oiled or greased duct a^{10} leading through the fixed hanger to the 40 exterior of the oscillatory head b , while the drip is retained by the upwardly extending brake flange f^3 .

It has been common practice in centrifugal work of this class heretofore, to couple 45 the motor shaft directly to the gyratory basket shaft by a flexible but permanent coupling, or in some cases to couple the motor shaft directly to the basket shaft by a centrifugal clutch coupling. In the present 50 invention the overhead motor shaft h is a continuously running shaft, and carries centrifugally acting clutch blocks h' which however may be disengaged from the surrounding clutch rim or pulley e' fast on the intermediate shaft e by means of pivoted levers h^2 , whose upper ends are normally thrust inward by the outward movement of the clutch blocks which may be opened apart by the upward movement of the conical slide 55 sleeve h^5 , which is raised and lowered by an engaging fork h^4 . When the conical clutch controlling member h^3 is depressed by the fork, the clutch blocks are free to engage the clutch rim under centrifugal action, but 60 when the clutch releasing member h^3 is

raised, the levers act to move inwardly the clutch blocks and disengage them from the clutch pulley e' .

The arrangement above described also is particularly applicable to our arrangement 70 for driving a battery of centrifugal machines from a line shaft in accordance with the principles explained in my co-pending application filed April 9, 1917, Serial Number 165,158, since the drive shaft of each 75 machine in that case would be permanently geared with the line shaft, while having a disconnectible and direct drive connection with the oscillatory basket shaft which does not transmit to the fixed bearings of the 80 driving shaft any lateral strain due to the oscillation of the basket shaft.

As shown in Fig. 1, the clutch mechanism 85 may be housed in a fixed hanger g whose lower end is provided with a suitable bearing for the support of the intermediate or transmission shaft e .

When stopping the machine at the end of each run or load, the driving clutch is disengaged in the manner described, and at the 90 same time the brake band is applied to the brake pulley f^4 so as to act directly upon the basket shaft without having to perform the extra duty of stopping the driving motor whose mass at this speed acquires great 95 momentum.

For the purpose of cooling the brake pulley f^4 , I provide on the interior thereof a series of inwardly projecting vanes f^6 , and between which are placed air-holes f^8 so as to 100 maintain a circulation of air through the rim of the pulley and thus carry away the heat generated by the action of the brake.

What I claim is:

1. A driving mount for centrifugal machines embracing in its construction an oscillatory bearing head provided with internal bearings for rotatably supporting the lateral and vertical thrust of the gyratory basket shaft, a curved bearing seat affording 110 a support for said bearing head above the plane of its center of oscillation, a rotary basket shaft supported on said internal bearings to oscillate with said head, a centralizing buffer having operative engagement with said bearing head to yieldingly oppose its oscillatory movements, and a power transmitting shaft mounted co-axially above said basket shaft and having jointed driving connection with said basket shaft, 115 substantially as described.

2. In a centrifugal machine the combination with a fixed hanger, of an oscillatory bearing head mounted upon said hanger by a universal-joint support located above the 125 center of oscillation, a centralizing buffer arranged above said universal-joint to engage said head and yieldingly oppose the oscillation thereof and resist the lifting of the bearing head from its support, a basket 130

shaft rotatably supported inside said head by means of bearings arranged respectively to receive the lateral and the vertical thrust of said basket shaft and means for rotating 5 said basket shaft, substantially as described.

3. In a centrifugal machine mount, the combination of a fixed hanger having a convex spherically curved bearing, an oscillatory bearing head provided with a concave 10 spherically curved bearing surface formed to rest and oscillate on said bearing seat above the center of oscillation, a rotary basket supporting shaft mounted on suitable thrust and lateral bearings inside said bearing head 15 to oscillate in unison therewith when rotating, a centralizing buffer arranged to engage said bearing head above its oscillatory seat, and a power transmitting shaft arranged above the basket shaft and in alignment therewith and having flexible coupling connection with said basket shaft for driving purposes, substantially as described.

4. In a centrifugal machine the combination of a fixed hanger, an oscillatory head 25 mounted thereon by a universal joint, a gyratory basket shaft supported on suitable bearings inside said bearing head, a centralizing buffer disposed interiorly of said bearing head, and a fixed member engaging 30 the inside of said buffer to support the buffer in position to afford a yielding resistance to the oscillation of the bearing head, and means for rotating said basket shaft, substantially as described.

5. In a centrifugal machine the combination of a fixed hanger, an oscillatory head supported thereon by a universal joint to permit oscillation, means for opposing a yielding resistance to said oscillation, said 40 bearing member being provided around its center of oscillation with a supplemental centralizing bearing to maintain the head in centralized position in case the head is lifted from its universal joint, a basket shaft rotatably mounted in said bearing head, and means for rotating said basket shaft, substantially as described.

6. In a centrifugal machine the combination of a fixed hanger, an oscillatory bearing head supported thereon by a universal joint engagement, said bearing head having also a supplemental centralizing bearing engagement with said hanger to maintain the centralization of the head when lifted from 55 its support, a centralizing buffer arranged to oppose a yielding resistance to the oscillation of said bearing head, and a rotary basket shaft suspended on bearings inside said bearing head and partaking of its oscillatory movement, substantially as described.

7. In a centrifugal machine the combination of a fixed hanger, an oscillatory bearing head supported in said hanger on a 60 universal joint located above the center of

oscillation, a supplemental centralizing bearing comprising a convexly curved ball portion surrounding said bearing head at its center of oscillation, and a correspondingly concavely curved member engaging said ball 70 portion and mounted to permit axial movement inside said fixed hanger, a centralizing buffer arranged to oppose yielding resistance to the oscillation of said bearing head, and a rotary basket carrying shaft supported 75 in bearings in said bearing head, substantially as described.

8. In centrifugal machines the combination of a fixed hanger, an oscillatory bearing head mounted thereon by a universal joint engagement, a supplemental spherical bearing surrounding the bearing head at its center of oscillation, a centralizing buffer arranged to form an internal engagement with said bearing head and a fixed buffer supporting member having engagement with the inside of said buffer, and a rotary basket shaft rotatably mounted for support in said bearing head, substantially as described.

9. In centrifugal machines the combination of the oscillatory bearing head provided intermediate of its ends with an inwardly projecting ledge, thrust bearings arranged above and below said ledge to support the vertical thrust of the basket shaft 95 in either direction, a rotary basket shaft supported on said thrust bearings and having lateral bearing engagement to permit rotation, an over-head power transmitting shaft alined with said basket shaft and having flexible driving connection therewith, substantially as described.

10. The combination of an oscillatory bearing head, a central basket shaft rotatably supported therein by suitable anti-friction lateral bearings and thrust supporting bearings, a sectional shouldered sleeve divided transversely into upper and lower sections each section having engagement with a lateral and a thrust bearing to rotatably 105 support the shaft, a suspended head detachably secured to the lower end of said shaft and provided with an upwardly extending external flange forming a brake pulley, substantially as described.

11. The combination of an oscillatory bearing head provided with internal anti-friction thrust and lateral bearings, a rotary shaft rotatably supported by said bearings, a suspended head detachably secured at the 110 lower end of said shaft and having an annular flange encircling said bearing head, said flange being provided with internal vanes and having perforations to maintain a circulation of air between the bearing head 120 and said flange, substantially as described.

12. A driving mount for a centrifugal machine embracing a fixed hanger, an oscillatory bearing head suspended therein by a universal joint, a rotary basket supporting 125

shaft suspended inside said bearing head to oscillate in unison therewith, an over-head non-oscillatory co-axial power transmitting shaft having flexible coupling connection 5 with said basket shaft, a non-oscillatory driving shaft alined with said transmission shaft and having clutch engagement with said power transmitting shaft, and means for dis-engaging at will the clutch connection 10 between said two shafts, substantially as described.

13. A driving mount for centrifugal machines embracing in combination an oscillatory bearing head, a basket supporting shaft rotatably mounted therein to oscillate therewith, a continuously running over-head driving shaft, an intermediate non-oscillatory power transmitting shaft having flexible coupling connection at its lower end 20 with the basket shaft, and having clutching engagement at its upper end with the over-head driving shaft, and means for operatively clutching together and for operatively dis-engaging the driving shaft with said intermediate shaft, substantially as described. 25

14. The combination of an oscillatory bearing head, a centrifugal basket shaft rotatably suspended therein to oscillate therewith, a continuously running over-head driving shaft, an intermediate power transmitting shaft flexibly coupled at its lower end with said basket shaft, a centrifugal clutch for operatively clutching together the driving shaft and the intermediate shaft, 30 and means operated at will to dis-engage the centrifugal clutch from operative driving position, substantially as described.

15. The combination of the fixed hanger, an oscillatory bearing head mounted therein 40 on a universal-joint, a centrifugal basket

shaft rotatably suspended inside said bearing head, a co-axial driving shaft mounted above said centrifugal shaft and flexibly coupled therewith, a centralizing buffer arranged inside said bearing head, a fixed 45 buffer supporting member arranged inside said buffer, and a buffer protecting ring mounted on the outside of said fixed buffer supporting member and having engagement with the adjacent portion of the said 50 oscillatory bearing head to afford protection to said buffer from contact with oil inside said bearing head, substantially as described.

16. In a suspension for a centrifugal machine the combination with a fixed hanger 55 provided with a convex spherical bearing seat, an oscillatory head having a concave bearing member adapted to fit over said spherical bearing seat, a basket-carrying shaft suspended on rotary bearings inside said oscillatory head, said bearing head being also provided with a supplemental convex spherical bearing engaging a concave bearing seat in said hanger in order to afford lateral support for said bearing head. 60

17. A suspension for a centrifugal machine embracing a fixed hanger having one convex spherical bearing seat and another concave spherical bearing seat whose surfaces are concentric about a common center, 70 an oscillatory head having two corresponding bearing members forming universal joint engagement with the aforesaid concentric bearings, and a vertical shaft suspended inside said bearing head on rotary bearings. 75

In witness whereof, I have subscribed the above specification.

EUGENE ROBERTS.
